JEWELED CROSS

David E. McAllister, 11 Elm St., Woodsville, N.H.

Filed Mar. 2, 1960, Ser. No. 59,595

Term of patent 14 years

(Cl. D45—16)

Fig. 1 is a perspective view of a jeweled cross showing my new design;

Fig. 2 is a side elevational view thereof;

Fig. 3 is a rear elevational view thereof; and

Fig. 4 is a top plan view of the same.

I claim:

The ornamental design for a jeweled cross, as shown.
